UNITED STATES PATENT OFFICE.

MORRIS F. WHITON, OF HINGHAM, MASSACHUSETTS, ASSIGNOR TO CHASE-SHAWMUT CO., OF BOSTON, MASSACHUSETTS.

DEVICE FOR APPLYING RAIL-BONDS TO RAILS.

SPECIFICATION forming part of Letters Patent No. 678,821, dated July 16, 1901.

Application filed September 24, 1900. Serial No. 30,928. (No model.)

To all whom it may concern:

Be it known that I, MORRIS F. WHITON, of Hingham, county of Plymouth, State of Massachusetts, have invented an Improvement in 5 Devices for Applying Rail-Bonds to Rails, of which the following description, in connection with the accompanying drawings, is a specification, like letters on the drawings representing like parts.

10 This invention has for its object to construct a device especially adapted to be used in applying rail-bonds to rails, and is particularly adapted for use in applying a rail-bond comprising an intermediate portion of any suitable shape and a pair of flat feet having on their faces a layer of solder for attaching the bond to the rails.

In accordance with this invention a rail-engaging frame is provided, which may be of 20 any suitable construction, and a pair of arms are pivotally or otherwise connected to said rail-engaging frame, having at their extremities bond-receiving supports adapted to act conjunctively to hold the flat feet of the bond 25 in engagement with the rails, and automatic means are provided for moving said arms and supports to press the bond against the rail with a constant pressure, so that when the solder melts by heating the rails the bond 30 will be pressed into firm contact with the rails. The parts will be adjustable to compensate for rails of different heights and widths.

Figure 1 shows in side elevation a device for use in applying rail-bonds embodying this 35 invention. Fig. 2 is a plan view of the device shown in Fig. 1, and Fig. 3 is an edge view of a rail-bond to which my device is especially designed to apply.

The rail-engaging frame, as herein shown, 40 consists of a pair of arms a a , rigidly connected together and disposed in parallelism and provided at their extremities with hooks a' or other suitable end portions to engage the tread of the rail, and a pair of depending arms a^2 a^2 , arranged at right angles to the aforesaid arms, or substantially so; yet so far as my invention is concerned this rail-engaging frame may be constructed in any other suitable manner.

45 The rail-engaging frame is provided with one or more limiting-stops b , two being here-

in shown, which are made as screws for the purpose of adjustment, and said stops pass through one of the cross-pieces by which the arms of the frame are rigidly connected together, and said stops are disposed to bear upon the edge of the foot of the rail when the frame is placed in position thereon. A pair of arms c , made independent of each other, are pivoted to the arms a^2 of the frame, each 55 of which bears at one extremity a bond-receiving support, herein shown as a rocker-plate c , which is adapted to bear upon one of the flat feet of the bond, and each arm bears at its opposite end a weight c^2 , by which it is 60 automatically moved. The weighted ends of the arms c form handles by which the bond-engaging ends of the arms may be manipulated, and when the bond-engaging ends of the arms are in engagement with the bond 65 a constant pressure thereon will be exerted by the weights. Any number of holes may be provided in the arms a^2 for the pivot-pins of the arms c for adjusting the position of said arms to different elevations, and the arms 70 may have any number of holes in them for the pivot-pins for adjusting the position of said arms back and forth.

It is designed and intended that the bond which is to be applied to the rail shall have 75 an intermediate portion and a pair of flat feet and that said flat feet shall have on their faces a layer of solder for attaching the bond to the rails. The bond having the layers of solder on its feet will be placed in position on the 80 rails and held fixed by the device forming the subject-matter of this invention, and the rails will then be heated, and when the solder melts by the application of heat to the rails said bond-engaging arms c will act automatically 85 to press the bond into firm contact with the rails for attachment thereto.

The bond-engaging arms c are constructed to act independently, so that if for any reason the bottoms of the rails should not occupy 90 the same horizontal plane each arm will conform itself to the plane of its particular rail.

I claim—

1. In a device for applying rail-bonds to rails, the combination of a rail-engaging frame, a pair of arms pivotally connected thereto, having bond-receiving supports at

their extremities, adapted to act conjunctively to hold a bond in position to be applied to the rail, automatic means for moving said arms and supports to press the bond against the rail with a constant pressure, and a limiting-stop on said frame for holding the frame with its arms and supports in position to apply the bond to the rail, substantially as described.

5 2. In a device for applying rail-bonds to rails, the combination of a rail-engaging frame, two independently-movable arms pivotally connected thereto, having at their extremities bond-receiving supports, adapted to act conjunctively to hold a bond in position 10 to be applied to the rail, and a limiting-stop on said frame for holding the frame with its arms and supports in position to apply the bond to the rail, substantially as described.

15 3. In a device for applying rail-bonds to rails, the combination of a rail-engaging frame, two independently-movable arms, pivotally connected thereto, having at their extremities bond-receiving supports, adapted to act conjunctively to hold a bond in position 20 to be applied to the rail, automatic means for moving said arms and supports to press the bond against the rails with a constant pressure, and a limiting-stop on said frame for 25

holding the frame with its arms and supports in position to apply the bond to the rail, substantially as described.

4. In a device for applying rail-bonds to rails the combination of a rail-engaging frame, a pair of arms pivotally connected thereto, having bond-receiving supports at 30 their extremities, adapted to act conjunctively to hold a bond in position to be applied to the rail, and a limiting-stop on said frame for holding the frame with its arms and supports in position to apply the bond to the rail, substantially as described.

5. In a device for applying rail-bonds, a rail-engaging frame having hooked arms to engage the rail and having a depending portion provided with an adjustable limiting-stop, and movable bond-holding arms pivotally connected to said frame which engage and hold a rail-bond in position on the rails, substantially as described.

In testimony whereof I have signed my name to this specification in the presence of two subscribing witnesses.

MORRIS F. WHITON.
